US0D1089272S

(12) **United States Design Patent** (10) Patent No.: US D1,089,272 S
Poulin (45) Date of Patent: ** Aug. 19, 2025

- (54) **DISPLAY SCREEN WITH GRAPHICAL USER INTERFACE**

(71) Applicant: **WAPP TECH CORP.**, Red Deer (CA)

(72) Inventor: **Donavan Paul Poulin**, Kelowna (CA)

(73) Assignee: **WAPP TECH CORP.**, Red Deer (CA)

(**) Term: **15 Years**

(21) Appl. No.: **29/998,876**

(22) Filed: **Apr. 15, 2025**

Related U.S. Application Data

- (63) Continuation of application No. 29/990,898, filed on Feb. 25, 2025, which is a continuation of application No. 29/939,488, filed on Apr. 26, 2024, now Pat. No. Des. 1,063,973, which is a continuation of application No. 17/657,213, filed on Mar. 30, 2022, now Pat. No. 11,971,812, which is a continuation of application No. 16/510,928, filed on Jul. 14, 2019, now Pat. No. 11,327,875.
